UNITED STATES PATENT OFFICE

W. OSCAR HICKEL, OF CLEVELAND, OHIO, ASSIGNOR TO ROUSE & HILLS,
OF SAME PLACE.

GAS-CARBURETOR.

SPECIFICATION forming part of Letters Patent No. 366,664, dated July 19, 1887.

Application filed March 24, 1886. Serial No. 196,370. (No model.)

To all whom it may concern:

Be it known that I, W. OSCAR HICKEL, of Cleveland, in the county of Cuyahoga and State of Ohio, have invented certain new and useful 5 Improvements in Gas-Carburetors; and I do hereby declare the following to be a full, clear, and exact description of the invention, such as will enable others skilled in the art to which it pertains to make and use the same.

10 My invention relates to improvements in gas-carburetors in which a novel arrangement of wicks is provided for giving a large evaporating surface and for thoroughly commingling the gases passing into the carburetor with the 15 vapors generated therein; also, a gas-drying apartment is provided with mechanism for packing or regulating the density of the drying material, to the end that the gases are delivered to the burner in good condition, and 20 that by varying the density of the drying material the pressure of the gas flowing to the burners is also varied at pleasure. The stop-valves for the induction gas-pipe and the filling-pipe of the container are connected with 25 their respective ports at right angles to each other, so that but one valve can remain open at a time, to the end that gas is not forced out into the room during the filling of the apparatus, and after the filling the valve of the induction 30 gas-pipe is not forgotten and left closed.

With these objects in view my invention consists in certain features of construction and in combinations of parts, hereinafter described, and pointed out in the claims.

35 In the accompanying drawings, Figure 1 is a side elevation in section of my improved apparatus. Fig. 2 is a cross-section on the line of $x-x$, Fig. 1, looking upward. Fig. 3 is a plan view of the duplex valve.

40 A represents the container, that is usually made of cast-iron, with a removable cast-iron cover, A'. Connected with the cover are the induction and eduction gas-pipes, respectively, B and C, and the filling-pipe D. Connected 45 with the body of the container, and part way down the side thereof, is the overflow-cock F. The pipe B has a valve, b, for stopping the flow of gas from the meter to the container while the latter is being filled. The pipe D has a stop- 50 valve, d, that is only opened for filling the container. These two valves, therefore, should

never both be closed or both open at a time. The two valves are therefore set with their ports at right angles to each other, and are then coupled in any suitable manner—for instance, 55 by a sleeve or connecting-rod, as shown in Fig. 3—so that both valves are operated simultaneously, the one being opened as the other is closed. By this means the valve b is not inadvertently left open while the container is being 60 filled, and therefore is avoided the escaping of gas into the room; also, after filling, the valve b is not inadvertently left closed, in which latter case there would be no pressure of gas at the 65 burners.

Inside the container, and depending from the cover thereof, are the hollow sheet-metal cylinders E and G. The former is of considerable length, reaching to near the bottom of the container. Coarse wire screens are arranged top 70 and bottom crosswise of the cylinder, and are held thus separated by the brace-wires e'. Ordinary candle-wicking is passed backward and forward through the meshes of the wire screen, the strands of the wicking running substantially parallel. In this manner a mass of wicking is formed that loosely fills the cylinder and extends from top to bottom thereof. 75

The pipe B discharges through the cover inside of this cylinder E. The cylinder, near 80 the upper end thereof, has openings E'. The cylinder G is comparatively short, as shown, and has two series of perforations, g and g', arranged circumferentially and near the bottom end thereof. Wicking is drawn through 85 the lower holes, g, and both strands extend to near the bottom of the container, where they are gathered and tied, by means of which the ends are prevented from tangling with each other, and also the wicking is brought in a 90 funnel shape. Above the holes g is a disk of wire-gauze, g'', that extends across the cylinder. This gauze is usually supported by two or three stronger wires arranged below the gauze and secured on either side of the cylinder. 95 The space above the gauze is filled, or nearly so, with layers of wicking, preferably wound spirally and placed layer above layer. On top of the wicking is a perforated head, H. This head fits loosely in the cylinder G, and 100 is moved vertically, to give more or less pressure upon the wicks, by a set-screw, H'. The

lower end of the screw has rigidly attached a broad flange, *h*, that operates between the head *H* and a plate, *H'*, that is secured to the head. The set-screw engages the head *H* at 5 one side of the center of the latter, by means of which the head cannot be turned with the set-screw. There is but little pressure required on the head *H*, and the broad flange *h*, located as aforesaid, is sufficient to hold the head *H* 10 in a horizontal position while such pressure is given to the head as is necessary. If the set-screw were in line with the axis of the head, the two might possibly turn together; but the turning of the head would be likely to roll the 15 wicking and displace it.

The eduction-pipe *C*, that with its branches leads to the burners, opens through the head *A* inside of the cylinder *G*. The container *A* is partially filled with some one of the lighter 20 products of hydrocarbon oil, usually gasoline—that is, up to the line of the cock *F*, that is left open during the filling for the purpose of gaging the depth of the liquid within. The liquid in the container is carried up by capillary attraction of the wicks in the cylinder *E*, and is evaporated and commingled with the gas entering through the pipe from the meter, the united product passing out at the holes *E'*. From thence its only means of escape is 25 either through the holes *g* or through the interstices of the wicking below. In either case it is further enriched by the vaporization about the wicking suspended from the cylinder *G*. From thence the gas passes up 30 through the drying-chamber. If the layers of wicking in this chamber are left in a loose condition, there is but little obstruction to the passage of the gas, which would have at the burners substantially the same pressure 35 as at the meter. The only effect in such case would be that the wicking operates as a drier and retains any atomized particles until they are converted into vapor, so that the gas, after 40 passing this drying-chamber, is in good condition for burning. By compressing this wicking, and thereby of course increasing its density, the passage of the gas through it is much retarded, so that the pressure at the burners 45 may be reduced as desired. The gas from the meter, after having been enriched in passing 50 through the carburetor, requires very much less pressure at the burner, and by turning down the set-screw *H'* this pressure of the gas at the burner may be regulated at pleasure. 55 The illuminating qualities of ordinary lighting-gas may be thus enriched from forty to sixty per cent., and this, too, at a trifling cost. Besides, the brilliancy of the flame is materially increased. Also, by regulating the press-

ure as aforesaid, all blowing at the burners 60 and irregularities of the flames are prevented.

I am aware that it is old to provide a gas-carburetor with one or more evaporating-chambers; also, that it is old to provide a carburetor with a drying-chamber having a 65 fibrous packing and provided with a platen, whereby the flow of gas may be regulated as well as deprived to a certain extent of its moisture; and hence I make no claim, broadly, to such construction. 70

What I claim is—

1. In a gas-carburetor, the combination, with a container having an overflow-cock, and an evaporating-chamber and drying-chamber located within the container, the latter being in a 75 plane above the overflow-cock, of a lid or cover having inlet and outlet pipes connected, respectively, with the evaporating and drying chambers, and an oil-inlet pipe, substantially as set forth. 80

2. The combination, with a gas carburetor having an overflow-cock, of a drying-chamber located therein in a plane above the overflow-cock, and having suitable drying material arranged therein, and a movable disk or platen 85 inside the drying-chamber and above the drying material therein, for compressing the drying material, substantially as set forth. 90

3. The combination, with a gas-carburetor having an overflow-cock and a drying-chamber located within said carburetor in a plane 95 above the oil-overflow cock, of drying material arranged in the drying-chamber, said drying material consisting of wicking coiled in a spiral form, with two or more layers piled the one upon the other, and a platen or disk for compressing the drying material, substantially as set forth. 100

4. The combination, with a gas-carburetor, of an oil-overflow cock secured in the side thereof, two or more evaporating-chambers located within the carburetor and in open relation with each other, a gas-supply pipe leading into the first of the evaporating-chambers, and a drying-chamber located in a plane above the oil-overflow cock in open relation with the last of the evaporating-chambers, said drying-chamber being in open relation with the discharge-pipe of the carburetor, the parts being arranged substantially as set forth. 105 110

In testimony whereof I sign this specification, in the presence of two witnesses, this 4th day of February, 1886.

W. OSCAR HICKEL.
